TUBE FLATTENING MEANS

Joseph G. Rosales, Los Angeles, Calif., assignor
to The Garrett Corporation, Los Angeles, Calif.,
a corporation of California

Application April 17, 1944, Serial No. 531,347

12 Claims. (Cl. 153—48)

1

This application is in part a continuation of my copending application, filed April 5, 1943, Serial No. 481,832, and now matured into Pat. No. 2,417,661, granted March 18, 1947, for Method and means for assembling heat exchangers having flattened tubes, and relates to an invention for manufacture of heat exchangers or intercoolers having flattened tubes therein, and relates in particular to a device for flattening tubes which have been assembled in banks.

It is an object of the invention to provide a simple device which will flatten round tubes after they have been arranged in a supporting frame work or housing in suitably spaced relation.

It is also an object of the invention to provide a tube flattening device having a plurality of cooperating jaws to simultaneously engage a plurality of tubes and which jaws may be actuated so as to flatten the tubes.

A further object of the invention is to provide for use within the housing of a heat exchanger a tube flattening device having a plurality of narrow fixed jaws in spaced relation and a plurality of movable jaws in cooperative relation thereto, with means for simultaneously moving the cooperating jaws toward each other through a predetermined distance so that the tubes will be flattened consistently to a predetermined dimension.

Further objects and advantages of the invention will be brought out in the following part of the specification.

Referring to the drawings which are for illustrative purposes only,

Fig. 1 is a side view of a preferred form of my invention.

Fig. 2 is an enlarged partly sectioned view showing the manner in which the jaw means of the device engages the tubes which are to be flattened.

Fig. 3 is an enlarged partly sectioned view taken as indicated by the line 3—3 of Fig. 2.

The tube flattening device shown in the drawings includes a support 12 of rectangular form so as to have the appearance of a flat rectangular plate as shown in Fig. 3, there being an opening 13 near the center thereof. A plurality of fixed jaw members 14 project from the front face of the support 12 in parallel relation. These jaw members 14 have the general form of flat bars of rectangular cross section standing on edge on the front face of the support 12. The jaw members 14 are preferably formed integrally with the support 12 and are disposed in spaced relation from end to end thereof. It will be noted that

2

the blade-like jaw members 14 extend full width of the support 12.

The jaw members 14 have aligned openings 25 therethrough to receive a pair of bar elements 16 which support movable jaw members 17 in cooperative relation to the fixed jaw members 14. Each of the bar elements 16 comprises a headed bar 18 having a short threaded section 21 opposite its head 19. The movable jaw members 17 have aligned openings 22 therethrough which closely fit the shank 20 of the screw or bar 18, and these movable jaws 17 are spaced along the shanks 20 of the bars 18 by spacer sleeves 23. As shown in Figs. 2 and 3, the final movable jaw 17, indicated by the numeral 17', has threaded openings 24 to receive the threaded ends 21 of the bars 18. The heads 19 of the bars 18 are preferably of the same external diameter as the sleeves 23 and are provided with sockets 25' engageable by a wrench for the purpose of turning the bars 18 so as to screw the threaded ends 21 thereof into the threaded openings 24 of the movable jaw member 17'. A feature of the arrangement shown in Figs. 2 and 3 is that the movable bars 17 may be assembled in the spaces between the fixed bars 24 and that the spacer sleeves 23 may be disposed in the openings 15, after which the bar 18 may be passed progressively through the openings 22 of the jaws 17 and the openings of the sleeves 23. The assembly of jaws 17 and sleeves 23 are held snugly together by compression resulting from the screwing of the bar 18 into the jaw member 17'.

The movable jaw members 17 comprise part of a movable unit including the bars 18 and the sleeves 23, which unit is moved by a lever 26 which is swingable on a transverse pin 27 in the opening 13 of the support 12. The forward end 28 of the lever 26 is positioned between adjacent movable jaws 17 and is adapted to engage the back face 29 of one of the movable jaws 17. The rear end 30 of the lever 26 is engageable by a lever 31 which actuates the jaws 17' and also serves as a handle projecting rearwardly from the support 12. This power unit P has an arm 32 lying alongside the lever 31 and being connected to the rear face of the support 12 by machine screws 33. The invention includes adjustable means for limiting the movement of the jaws 17 under power so that the tubes will be flattened to exactly the desired extent. This adjustable means comprises a screw 34 which is threaded through the lever 32 in such position that the end of the screw 34 will confront the face 36 of the lever 30.

A spring 37, disposed around the projecting end of the screw 34, exerts a force to return the lever 30 to its initial position, and also to return the jaws 17 to initial or inactive position after the actuating power has been released.

The lever 31 is swingably attached to the arm 32 by a pivot 41 and on the rearward end of the arm 32 there is a cylinder 42 having therein a fluid operated piston 43 which actuates means 44 to swing the lever 31 in the direction indicated by the arrow 45' of Fig. 1. This actuating means 44 is shown as a toggle which acts between a pivot 45 carried by the arm 32 and a pivot 46 carried by the lever 31 to produce the desired movement of the lever 31 when force is applied to the central portion of the toggle 44 as the result of forward movement of the piston 43 by fluid pressure, such as air pressure, received through a flexible conduit 48 connected to a passage 49 which extends through a handle member 50 attached to the rear end of the piston 43. An air valve 52, arranged to be operated by a manually engageable button 53, controls the flow of air through the passage 49 to the cylinder 42.

The handle means, provided by the cylinder 42 and the projecting handle 50, makes it possible for a worker to easily support the tube flattening device in a position wherein a portion thereof extends into the shell of an intercooler to engage the tubes which are to be flattened.

In Fig. 2 I show several rows of tubes 9. Those tubes indicated by the numeral 9' and spaced along the line a—a have been flattened. On either side of the line a—a rows of tubes 9 are spaced along the lines b—b. In the normal use of the tube flattening device, the first row of tubes is disposed along the line a—a and are flattened as shown. Thereafter said tubes 9 are placed in the rows indicated by the lines b—b. The tube flattening device is then brought into the position shown in Fig. 2, so that the cooperating pairs of jaws 14 and 17 straddle unflattened tubes. The front edges of the jaws 14 and 17 are chamfered so as to give them such thinness that they will enter the spaces between the tubes, and shoulders 58 are provided along the front portions of the jaws 14 and 17 to engage the edge portions of tubes which have been previously flattened. When the tube flattening device has been brought into the position shown in Fig. 2, the operator actuates the power means so that relative movement of the jaws 14 and 17 will be produced to flatten the tubes engaged thereby to a width predetermined by the setting of the adjusting screw 44.

I claim as my invention:

1. In a device adapted to be passed into the interior space of a supporting structure for flattening tubes arranged in side by side relation in said supporting structure, the combination of: a rectangular supporting member having a plurality of blades extending therefrom in side by side relation to form a plurality of spaced stationary jaws, there being rows of aligned openings through said stationary jaws perpendicular to the faces of said jaws; bar elements extending through said openings and being slidable therein; movable blades mounted rigidly on said bar elements to form movable jaws in spaced relation to said stationary jaws, and forming with said bar elements a movable jaw unit; handle means extending rearwardly from the back of said supporting member, said handle means comprising a power means and means to actuate said power means; and a lever arranged to be moved by said power means, one end of said lever having

operative engagement with said movable jaw unit to move the same in a direction to bring said movable jaws closer to said stationary jaws.

2. In a device adapted to be passed into the interior space of a supporting structure for flattening tubes arranged in side by side relation in said supporting structure, the combination of: a rectangular supporting member having a plurality of blades extending therefrom in side by side relation to form a plurality of spaced stationary jaws, there being rows of aligned openings through said stationary jaws perpendicular to the faces of said jaws; bar elements extending through said openings and being slidable therein; blades disposed in the spaces between said stationary jaws so as to form movable jaws in cooperative relation to said stationary jaws, said movable jaws having openings therethrough aligned with said openings through said stationary jaws; bars extending through said openings of said jaws; spacer means on said bars to hold said movable jaws in fixed relation to said bars and thereby form a movable jaw unit, said spacer means being slidable in said openings of said stationary jaws; handle means extending rearwardly from the back of said supporting member, said handle means comprising a power means and means to actuate said power means; and a lever arranged to be moved by said power means, one end of said lever having operative engagement with said movable jaw unit to move the same in a direction to bring said movable jaws closer to said stationary jaws.

3. In a device for flattening tubes which are arranged in rows and supported in a position extending from one plate to another, there being narrow spaces between said tubes, the combination of: a support; first jaw members connected to said support in parallel relation, said jaw members presenting relatively slender edge walls for engagement with said tubes and for entering the spaces between said tubes; second jaw members to cooperate with said first jaw members, said second jaw members also having slender edge portions capable of entering said spaces between said tubes; means connecting said second jaw members so that they will move in unison; means extending from the back of said support for producing relative movement of said second jaw members toward said first jaw members; and handle means, of which at least a portion of said last mentioned means forms at least a part, for supporting and manipulating said device to and from operative positions.

4. In a device for flattening tubes which are arranged in rows and supported in a position extending from one plate to another, there being narrow spaces between said tubes, the combination of: a support; first jaw members connected to said support in parallel relation, said jaw members presenting relatively slender edge walls for engagement with said tubes and for entering the spaces between said tubes; second jaw members to cooperate with said first jaw members, said second jaw members also having slender edge portions capable of entering said spaces between said tubes and having, rearwardly of said slender edges, offset shoulders adapted to engage previously flattened tubes so as to limit the penetration of said slender edge portions between the tubes; and means for producing relative movement of said second jaw members toward said first jaw members.

5. In a device for flattening tubes which are arranged in rows and supported in a position ex-

tending from one plate to another, there being narrow spaces between said tubes, the combination of: a support; first jaw members connected to said support in parallel relation, said jaw members presenting relatively slender edge walls for engagement with said tubes and for entering the spaces between said tubes; second jaw members to cooperate with said first jaw members, said second jaw members also having slender edge portions capable of entering said spaces between said tubes; means connecting said second jaw members so that they will move in unison; means extending rearwardly from said support for producing relative movement of said second jaw members toward said first jaw members; and shoulders on said jaw members for engaging previously flattened tubes and thereby properly position said jaws with respect to the tubes which are to be flattened.

6. In a tube flattening device of the character described, the combination of: a support defining a rectangular area; fixed jaw members extending forwardly from said support, said jaw members comprising relatively narrow plates disposed in parallel relation with spaces therebetween, there being openings through said plates; bar means slideable in said openings; movable jaw members secured to said bar means in said spaces between said fixed jaw members and in cooperative relation to said fixed jaw members; and means carried by the rear face of said support for moving said bar means so as to carry said movable jaw members toward said fixed jaw members.

7. In a tube flattening device of the character described, the combination of: a support; fixed jaw members extending forwardly therefrom, said jaw members comprising relatively narrow plates disposed in parallel relation with spaces therebetween, and having openings therethrough; bar means slideable in said openings; movable jaw members secured to said bar means in said spaces between said fixed jaw members and in cooperative relation thereto; and means for longitudinally moving said bar means so as to carry said movable jaw members toward said fixed jaw members.

8. In a tube flattening device of the character described, the combination of: a support; fixed jaw members carried by said support and projecting therefrom in parallel spaced relation, said jaw members having axially aligned bearing bores extending therethrough; a plurality of movable jaws arranged in the spaces between said fixed jaw members and adapted to cooperate therewith; a plurality of spacer sleeves interposed between said movable jaw members and maintaining them in spaced relation, said sleeves being partially received in said bores and having sliding bearing engagement therewith; a bar extending through said movable jaw members and said sleeves and on which said movable jaw members and sleeves are stacked and secured to form a movable jaw assembly; and means for moving said movable jaw assembly with reference to said fixed jaw members.

9. In a tube flattening device of the character described, the combination of: a support; a plurality of fixed jaw members carried by said sup-

port and projecting therefrom in spaced relation; a plurality of movable jaw members arranged in fixed spaced relation to each other in an assembly which is movable relative to said fixed jaw members, said movable jaw members being interposed between said fixed jaw members and adapted to cooperate therewith; means whereby said movable jaw assembly is guided with reference to said support and fixed jaw members; and means including a lever pivoted on said support and having a head projecting between an adjacent pair of said movable jaw members and provided with rounded surfaces in bearing engagement with opposed surfaces of said jaw members, for moving said movable jaw assembly relative to said fixed jaw members.

10. In a tube flattening device of the character described, the combination of: a support; a plurality of fixed jaw members carried by said support and projecting therefrom in spaced relation; a plurality of movable jaw members secured together in an assembly which is movable relative to said support and said fixed jaw members, said movable jaw members being interposed between the respective fixed jaw members and adapted to cooperate therewith; handle means projecting from said support; a lever pivoted on said support having one end operatively related to said movable jaw assembly to transmit movement thereto and having its other end arranged in spaced relation to said handle member; and a stop, adjustably mounted on said handle means and adapted to engage said lever to limit the movement of said movable jaw members toward said fixed jaws.

11. A tube flattening device as defined in claim 10, including power multiplying means comprising: a bell crank lever pivoted on said handle means and engaging said lever opposite said stop; and a coil spring interposed between said handle and said lever and piloted on said stop for spreading said fixed and movable jaw members.

12. In a tube flattening device of the character described, the combination of: a support; a row of fixed jaw members including relatively narrow portions disposed in parallel relation and with spaces therebetween; movable jaw members disposed in said spaces between the fixed jaw members and including relatively narrow portions in substantially parallel relation with said fixed jaw members; and means for effecting rectilinear movement of said movable jaw members toward said fixed jaw members longitudinally relative to said row while maintaining the narrow portions of the respective movable jaw members and fixed jaw members in parallelism.
